UNITED STATES PATENT OFFICE

93,333

DESIGN FOR A VANITY BOX

Peggie Dorée-Spearman, Paris, France

Application July 12, 1934, Serial No. 52,563
In France April 19, 1934

Term of patent 3½ years

To all whom it may concern:

Be it known that I, PEGGIE DORÉE-SPEARMAN, born PAINTER-DORÉE, a subject of Great Britain residing at Paris, 5 Square Thiers in the county of Seine and State of France have invented a new, original, and ornamental Design for a Vanity Box, of which the following is a specification, reference being had to the accompanying drawing, forming part thereof.

I claim:—

The ornamental design for a vanity box, as shown.

PEGGIE DORÉE-SPEARMAN.
